(57) **CLAIM**

The ornamental design for a H4 phone holster, as shown and described.

DESCRIPTION

FIG. 1 is a perspective view of one embodiment of the H4 phone holster, showing my ornamental design;
FIG. 2 is a front elevation view of the ornamental design of FIG. 1;
FIG. 3 is a rear elevation view of the ornamental design of FIG. 1;
FIG. 4 is a left side elevation view of the ornamental design of FIG. 1;
FIG. 5 is a right side elevation view of the ornamental design of FIG. 1;
FIG. 6 is a bottom plan view of the ornamental design of FIG. 1;
FIG. 7 is a top plan view of the ornamental design of FIG. 1; and,
FIG. 8 is a perspective view of the ornamental design of the H4 phone holster in an open position.
The broken line portions are for illustration purposes only and form no part of the claimed design.
